UNITED STATES PATENT OFFICE

100,266

DESIGN FOR A COMBINED DISPLAY RACK AND SOLDER BARS CONTAINED THEREIN

Ernest V. Halligan, Providence, R. I.

Application February 8, 1936, Serial No. 61,044

Term of patent 7 years

To all whom it may concern:

Be it known that I, Ernest V. Halligan, a citizen of the United States of America, residing in Providence, county of Providence, State of Rhode Island, have invented a new, original, and ornamental design for a Combined Display Rack and Solder Bars Contained Therein, of which the following is a specification, reference being had to the accompanying drawing, forming a part thereof.

Fig. 1 is a face view of the combined display rack and solder bars contained therein, showing my design, the figure being shaded to indicate the difference in colors in different portions of the article; and the dotted lines indicating perforated divisions between the individual elements;

Fig. 2 is a side elevational view;

Fig. 3 is a perspective view of one of the individual elements thereof, the figure being shaded to show the contour of the element.

I claim:

The ornamental design for a combined display rack and solder bars contained therein, substantially as shown and described.

ERNEST V. HALLIGAN.
